Attorney.

UNITED STATES PATENT OFFICE.

CLEM FRAZIER AND JAY ASHMORE, OF BIGGS, ILLINOIS.

INFLATION-VALVE.

1,232,272.

Specification of Letters Patent.

Patented July 3, 1917.

Application filed March 10, 1917. Serial No. 153,925.

To all whom it may concern:

Be it known that we, CLEM FRAZIER and JAY ASHMORE, citizens of the United States, residing at Biggs, in the county of Mason and State of Illinois, have invented certain new and useful Improvements in Inflation-Valves, of which the following is a specification.

This invention relates to inflation valves for the pneumatic tires of motor vehicles; and it consists of a cap, as hereinafter fully described and claimed, for inclosing the upper end of the valve casing and enabling access to the valve to be had with great facility.

In the drawings, Figure 1 is a side view of the casing of an inflation valve provided with a cap according to this invention. Fig. 2 is a side view partially in section and showing the cap when removed from the casing. Fig. 3 is a plan view of the cap.

The inflation valve is of any approved construction suitable for attachment to a pneumatic tire. The casing 2 of the valve is tubular and is screwthreaded externally, and it has a flange 3 at its lower end for engaging with the air tube of the tire. The casing is open at its upper end so that a suitable pin or instrument may be thrust into it to open the valve 4 in the usual way. A cap is provided for inclosing the upper end of the valve casing, and keeping out dirt and water. In order that this cap may be removed and replaced with great facility, and may be securely locked to the casing when in place, it is formed of two similar halves 5 and 6 which form a tubular cap when pressed together. These two halves have a hinge 7 at their upper end, and this hinge is made as watertight as possible. The two halves have internally screwthreaded jaws 8 at their lower end portions which are adapted to engage with the screwthreaded valve casing 2.

The upper parts of the cap have recesses 9 which are clear of the screwthreads of the casing, and a flange 10 is provided at the bottom of the cap on each half of it. The lower portion 12 of the cap is conical and is largest at its lower end where it joins onto the flanges 10. The middle part of the cap above its conical portion is provided with lateral projections or lugs 14, which are

preferably screwed into it, and a split spring ring 15 is provided and is arranged to slide on the lower part of the cap between the lugs 14 and the stop flanges 10.

When the ring 15 is forced downwardly, as shown in Fig. 1, it clamps the halves of the cap securely to the valve casing. When the ring is raised into engagement with the lugs 14 it spreads the halves of the cap apart, and permits it to be lifted clear of the casing so that free access to the valve can be had.

The split ring is slipped over the cap before the lugs 14 are fastened in place, and the flanges 10 prevent it from slipping off downwardly. The lugs 14 are hook-shaped and project downwardly, and the upper edge of the split ring is beveled so that it will spread the halves of the cap apart when it is pressed upwardly against the lugs.

What we claim is:

1. A cap for an inflation valve, formed of two sections pivotally connected at their upper ends and having jaws at their lower ends for engaging with the valve casing, said cap having also a conical portion at its lower end and two laterally projecting lugs at its middle part, said lugs having downwardly inclined outer end portions, and a locking ring slidable on the cap between the said conical portion and the said lugs and operating to spread apart the said jaws when pressed upwardly against the inclined end portions of the lugs.

2. A cap for an inflation valve, formed of two halves which are dust proof when pressed together, said halves having a dust proof hinge at their upper ends and having jaws at their lower ends for engaging with the valve casing, said cap having also a conical portion at its lower end and two laterally projecting lugs having downwardly inclined end portions, and a locking ring slidable on the cap between the said conical portion and the said lugs and operating to spread apart the said jaws when pressed upwardly against the inclined end portions of the lugs.

In testimony whereof we affix our signatures,

CLEM FRAZIER.
JAY ASHMORE.
